UNITED STATES PATENT OFFICE.

SAMUEL W. SPARGER, OF DURHAM, NORTH CAROLINA.

BOOK-HOLDER.

985,851.

Specification of Letters Patent.

Patented Mar. 7, 1911.

Application filed February 17, 1910. Serial No. 544,423.

To all whom it may concern:

Be it known that I, SAMUEL W. SPARGER, a citizen of the United States, residing at Durham, in the county of Durham and 5 State of North Carolina, have invented a new and useful Book-Holder, of which the following is a specification.

This invention relates to book holding attachments for telephones and is more particularly designed to hold directories and the like, one of the objects of the invention being to provide a holder which can be readily connected to the telephone without the use of clamps or other separate devices.

15 Another object is to provide a holder of this character designed to support an advertising card or the like.

With these and other objects in view the invention consists of certain novel details 20 of construction and combinations of parts hereinafter more fully described and pointed out in the claim.

In the accompanying drawings the preferred forms of the invention have been 25 shown.

In said drawings:—Figure 1 is a front elevation of a portion of a wall telephone having the holder attached thereto. Fig. 2 is a rear elevation of the holder, portions thereof 30 of being shown in section. Fig. 3 is a central longitudinal section through the holder, said section being on an enlarged scale. Fig. 4 is a view similar to Fig. 1 and showing a modified form of holder upon the telephone. Fig. 5 is a rear elevation of the holder shown 35 in Fig. 4.

Referring to the figures by characters of reference A designates the back board of the wall telephone, the same being secured to 40 the wall in the usual manner, as by means of screws *a* extending through the upper corner portions thereof.

One form of directory holder designed to be used in connection with the telephone, 45 consists of a box preferably formed of metal and open at its top, said box being indicated at 1 and the back 2 thereof being extended upwardly above the open top and being provided with an aperture 3 for the reception 50 of a supporting hook or nail which can be used for holding the device at points removed from the telephone. Cleats 4 are formed along the side and bottom edges of the front of the box and form a pocket 55 into which a card may be placed, the said card bearing suitable advertising matter.

The upper ends of the side cleats are preferably connected by a cross strip 6 back of which the card can be inserted into engagement with the cleats.

60

Upper and lower guide sleeves or strips 7 are secured transversely upon the back of the box and mounted within the upper one of these sleeves is a slide 8 having stop projections 9 extending downward from its 65 ends so as to prevent the slide from being withdrawn from its guide sleeve. A diagonally extending slot 10 is formed in each end portion of this strip 8 and extends upwardly and inwardly from the stop projection 9 adjacent thereto.

A strip 11 is slidably mounted within the lower guide sleeve 7 and is provided at its ends with upstanding projections 12 whereby withdrawal of the strip from the sleeve 75 is prevented.

When it is desired to attach the holder to a telephone, the strip 8 is extended beyond one side of the box and is inserted between the wall and the board A so as to bring the 80 slotted portion of the strip into engagement with the screw *a*. It will be seen therefore that the strip can be slipped onto this screw and will thus hold the box close to the side of the board A. The lower strip 11 can 85 then be forced back of the board A and will, obviously coöperate with the strip 8 so as to hold the box against displacement. With a box thus located close to and at one side of the telephone, the directory can be 90 placed therein and will always be convenient of access. Moreover if the holder is given to the subscriber for advertising purposes, an advertising card or the like may 95 be located within the pocket 5.

By forming the strips 8 and 11 in the manner described it becomes possible to attach the holder to either side of the telephone.

Instead of using slidable strips for the 100 purpose of engaging the telephone and supporting the box, said box may be provided upon its back with downwardly extending hooks 13 while additional hooks 14 may be arranged at the sides of the back close to 105 the bottom thereof. These hooks are all so proportioned that, by placing the box above the board A, the same can be forced downward so as to bring the hooks 14 into engagement with the side edges of the board 110 while the hooks 13 are brought into engagement with the top edge thereof. The box

will then be held as shown in Fig. 4. It is of course to be understood that a single hook 13 may be employed instead of two hooks. In both of the devices shown a 5 pocket is formed in the front face for the reception of an advertising card or the like, but it is to be understood that if preferred such a pocket may be dispensed with, and, if desired, advertising matter may be 10 printed or otherwise displayed upon the front face of the box.

Various changes can of course be made in the construction and arrangement of the parts without departing from the spirit or 15 sacrificing any of the advantages of the invention as defined in the appended claim.

What is claimed is:—

The combination with the back board of a telephone, of a book receptacle open at the 20 top, a guide secured to and extending transversely of the back of the receptacle, attach-

ing means extending from the back board, a support engaging strip slidably mounted within and projecting beyond the ends of the guide, said strip having integral means 25 at the ends thereof and coöperating with the guide for limiting the movement of the strip, there being inclined slots within the end portions of the strip for the reception of said attaching means, said strip being 30 shiftable beyond either side of the receptacle and coöperating with the attaching means to hold the receptacle against one side of the back board.

In testimony that I claim the foregoing 35 as my own, I have hereto affixed my signature in the presence of two witnesses.

SAMUEL W. SPARGER.
